RESISTANCE UNIT

Hugh A. Triplett, Wilmette, and Allan Ramsey, Evanston, Ill., assignors to Schweitzer & Conrad, Inc., Chicago, Ill., a corporation of Delaware

Application May 17, 1932, Serial No. 611,850

20 Claims. (Cl. 201—67)

This invention relates to electric resistors in general and more particularly to fixed current limiting resistors which are adapted for use on comparatively high voltage systems.

5 It is one of the objects of the present invention to provide a sturdy resistor unit which may be mounted outdoors and wherein the resistance element is protected from vermin or other animal life, dust, moisture or the like.

10 It is an object of the present invention to provide a current limiting resistor of a form suitable for convenient manufacture and assembly, as well as for convenient repair and replacement.

The chief object of the present invention is to 15 provide a resistor of improved construction, particularly adapted to facilitate the dissipation of heat. Thereby compactness is obtainable without sacrificing permanence or weather resisting qualities. Also, due to high heat dissipating 20 ability, such resistors may be placed in power circuits, as in a transformer circuit carrying 10, 15 or more amperes.

In carrying out the above object we have provided different structural members to perform 25 different functions. Thus the resistor supporting sleeve may be made of a material or in a form to adapt it to expansion or contraction incident to variation of temperature due to current flow. The supporting member may be made of suitable 30 structural material or form to adapt it to perform its mechanical supporting and electrical insulating function without being subject directly to the heat of the resistor. The enclosing sleeve is made of a vitreous material, for example, glass, which 35 does not deteriorate by weathering or electrical leakage, and is not subjected to the expansion and contraction of the part which directly supports the wire resistance. In one form of the present invention the ends of the unit are provided with 40 heat radiating flanges or fins. In another embodiment of the present invention the unit is so constructed as to permit the natural circulation of air therethrough while maintaining the resistance wire itself closed off from the atmosphere. 45 This unit comprises a vertically extending hollow cylindrical insulating core on the outside of which is wound a wire resistor which is protected from the atmosphere by a glass sleeve 50 surrounding the unit and end members closing off the space between the sleeve and the core at the ends while leaving the hollow interior of the cylindrical insulating core open. As the unit heats, convection currents will circulate through 55 the core cooling the inside thereof while heat is at

the same time being radiated outwardly of the outer sleeve.

The attainment of the above and further objects of the present invention will be apparent from the following specification taken in conjunction with the accompanying drawing forming a part thereof.

In the drawing:

Figure 1 is a half-sectional view of one form of the present invention;

Figure 2 is a half-sectional view of a hollow core type of unit embodying the principles of the present invention; and

Figure 3 is a top view of the unit shown in Figure 2.

The resistor unit shown in Figure 1 comprises a core 80 of porcelain or other suitable ceramic insulation having heat insulating members 81—82 secured to the ends thereof in any suitable manner, as by means of screws threaded directly into tapped holes in the insulator or into tapped inserts cemented or otherwise secured in sockets formed in the core 80. The core 80 provides the mechanical strength for the unit and fixedly 20 spaces and supports heads 87 and 88. An insulating sleeve or cylinder 85 surrounds the core 80 and rather loosely embraces the insulating members 81—82. The sleeve 85 has sufficient play 25 with respect to the plates 81 and 82 and adjacent parts as to permit free contraction and expansion of the sleeve due to thermal changes caused by variations of current in the resistance wire 86. The sleeve is thus free to contract and expand not only axially, but also radially. The sleeve 85 is 30 provided with a helical groove in which lies a resistor wire 86 that comprises a resistance wire such as nichrome or chromel wound into an open helix of small diameter, the convolutions of the coil being spaced apart so as to avoid contacting 35 with one another, particularly when they are wound in place in the helical groove in the member 85. The end closure members comprise castings 87—88 of bronze or other suitable conducting material secured in place by means of screws 40 89 threaded into inserts in the heat insulating members 81—82. The flanged heads 87 and 88 provide annular seats containing suitable gaskets for maintaining a substantially tight connection 45 with the glass enclosing sleeve 6. This sleeve is supported radially and axially on said flanged heads with suitable radial and axial gaskets interposed. Plates 90 of brass or other suitable conducting material are interposed between the end members 87 and the members 81—82. These 50 55

brass plates comprise anchors for the ends of the resistor wire 86. Heat radiating discs 92-92 are secured to each of the end castings 87-88. The discs have outwardly extending fins that afford good heat radiating surfaces and thereby reduce the temperature of the ends of the resistor unit. While only two heat radiating discs have been herein shown at each end of the unit it is to be understood that a greater or lesser number may be used as desired, or the discs may be entirely omitted from one end without departing from the spirit of the present invention.

Reference may now be had to Figures 2 and 3 wherein a different form of resistor unit is shown. The resistor wire is indicated at 100 and it is wound in a helical groove formed on the outer side of a hollow cylindrical sleeve of insulation 101 of lava or the like. The upper closure member comprises a rim 102 of somewhat larger diameter than the diameter of the core. The rim is slipped over the end of the core and constitutes a terminal for the wire 101. The end of the wire 101 is secured in a terminal clip 103 formed on the inside of the rim 102, said wire being firmly clamped in place by means of a screw 104. The end of the rim 102 is provided with a circular groove that fits over the end of a glass sleeve 106 and is sealed thereto by means of a suitable packing 107 of asbestos, rubber, or the like. The rim 102 is held in place upon the insulating core 101 by means of a pair of semi-circular members 108 and 109 that together comprise a circle fitting into a groove 111 in the end of the core 101. The split ring members 108 and 109 are secured to the continuous ring 102 by means of a number of screws 112 thereby holding the ring 102 against withdrawal. A suitable sealing gasket or packing is interposed between the ring members 108-109 and the core 101 to seal the end of the chamber formed between the core 101 and the glass sleeve 106.

The ring 102 is provided at one end with means for mounting the same. This means comprises a pair of arms 115 and 116 formed integrally with the ring 102 and united by an integrally formed portion 117 that is adapted to seat on an insulator and be secured thereto, as indicated in Figure 9. The portion 117 comprises a terminal lug for extending the circuit from the resistor unit.

The lower end of the core 101 is provided with a closure cap of a construction substantially identical to that at the upper end of the core. A further description of this cap need therefore not be given.

The unit shown in Figure 9 is preferably mounted in a vertical position on a pair of insulators, as shown. These insulators hold the rings 102-102 in definite spaced relation independently of the glass sleeve 106. Air will naturally circulate through the inner core and effectively cool the same. At the same time there is the natural dissipation of heat through the outside of the glass sleeve 106. By this arrangement a comparatively large current can be carried without overheating the resistance unit.

In compliance with the requirements of the patent statutes we have herein shown and described a few preferred embodiments of our invention. It is however to be understood that the invention is not limited to the precise constructions herein set forth, same being merely illustrative of the principles of the invention.

What we consider new and desire to secure by Letters Patent is:

1. A high tension current limiting resistor,

comprising the combination of a pair of metallic end pieces, an inner core of electrical insulation forming a rigid connection between the end pieces, a sleeve of heat resistant insulation surrounding the core and being supported to permit free expansion and contraction with respect to the said end pieces independently of the expansion and contraction of said core, and a resistance wire wound on said sleeve.

2. A high tension current limiting resistor, 10 comprising the combination of a pair of metallic end pieces, an inner core of electrical insulation forming a rigid connection between the end pieces, a sleeve of heat resistant insulation surrounding the core and being supported to permit free expansion and contraction with respect to the said end pieces independently of the expansion and contraction of said core, and a resistance wire wound on said sleeve, and a vitreous weather resistant sleeve spaced radially 15 from the resistance wire and sealed to said metallic end pieces to provide a non-deteriorating enclosure for said resistance wire.

3. A resistor comprising an inner supporting core and, surrounding the same, a sleeve of insulation, a wire resistor mounted on the sleeve, an outer sleeve of insulation surrounding the first sleeve, end caps secured to the inner core and forming a seal with the outer sleeve, and a metallic end plate comprising a terminal interposed between the first named sleeve and at 25 least one of the end caps.

4. A resistor comprising an inner supporting core and, surrounding the same a sleeve of insulation, a wire resistor mounted on the sleeve, 35 an outer sleeve of insulation surrounding the first sleeve, end caps secured to the inner core and forming a seal with the outer sleeve, a metallic end plate comprising a terminal interposed between the first named sleeve and at least one of the end caps, and a heat insulating member interposed between the end plate and the supporting core.

5. A resistor unit comprising a pair of concentric hollow cylindrical insulating members, a 45 resistor wire between the two, closure members at the ends of the two first mentioned members insulated from one another and closing the space between the two cylindrical members, the ends of the inner cylindrical member being open to 50 atmosphere to permit the natural circulation of air therethrough.

6. A resistor unit comprising a hollow cylindrical core of insulation open to the atmosphere 55 at the top and bottom to permit a natural circulation of air therethrough from outside the unit, a resistance wire on the outside of the core, a sleeve surrounding the core and spaced therefrom, and end closure members securing the sleeve to the core and closing off the space between the sleeve and the core, said end members comprising terminals for the ends of the resistance wire.

7. A resistor unit comprising a hollow cylindrical core of insulation open to the atmosphere 65 at the top and bottom to permit a natural circulation of air therethrough from outside the unit, a resistance wire on the outside of the core, a sleeve surrounding the core and spaced therefrom, and end closure members securing the 70 sleeve to the core and closing off the space between the sleeve and the core, said end members comprising terminals for the resistance wire and having mounting means extending therefrom for mounting the unit.

8. A resistor unit comprising a hollow cylindrical core of insulation open to the atmosphere at the top and bottom to permit a natural circulation of air therethrough from outside the 5 unit, a resistance wire on the outside of the core, a sleeve surrounding the core and spaced therefrom, and end closure members securing the sleeve to the core and closing off the space between the sleeve and the core, said end members 10 being secured to the core by means including split rings inserted into peripheral grooves in the core and secured to the end members.

9. An electrical device comprising a core of insulation having external peripheral grooves at 15 the ends thereof, a sleeve surrounding the core and spaced therefrom, a wire resistor disposed in the space between the core and the sleeve, end members securing the sleeve to the core and closing off the space between the sleeve and the 20 core, said end members being secured to the core by means including split rings inserted into the peripheral grooves and secured to the end members.

10. A device of the class described comprising 25 a hollow cylindrical insulating member open to atmosphere at both ends, a pair of metallic clamps embracing the opposite ends thereof and comprising terminals, a coil wound around the cylindrical member between the clamps and connected at its ends to the respective clamps, and 30 a tube of insulation spaced from the coil and surrounding the insulating member and sealed to the two clamp members.

11. In combination, a substantially cylindrical 35 body of refractory insulation having peripheral grooves at its ends, a resistor on the body between the grooves, a sleeve surrounding the body of insulation and terminating in rims at its two ends, and split rings extending into the grooves and 40 removably secured to the rims, whereby the rims are held by the rings and hold the rings against retraction from the grooves.

12. A resistor unit comprising a hollow tubular body of frangible insulation, a resistor wire 45 wound around the outside thereof, a glass tube surrounding the insulation and spaced from the resistor wire, flanged end members comprising terminals at the opposite ends of the body of insulation and sealing the space between the glass 50 tube and the body of insulation, a yielding packing between the end members and the glass tube maintaining the seal between the end members and the glass tube while permitting a limited relative shifting between them under expansion 55 and contraction incident to thermal changes and means independent of the glass tube for holding said end members in fixed insulated relation, said hollow tubular body being mounted on said end members with sufficient free play to permit 60 thermal contraction and expansion.

13. A resistor unit comprising a hollow tubular body of frangible insulation, a resistor wire wound around the outside thereof, a glass tube surrounding the insulation and spaced from the 65 resistor wire, the space between the resistor and the glass tube being filled with a gaseous medium to facilitate the dissipation of heat radially outwardly of the unit, flanged end members comprising terminals at the opposite ends of the body 70 of insulation and sealing the space between the glass tube and the body of insulation, means for mounting the end members in place comprising split rings separate from the end members and radially contractible into indentations in the body 75 of insulation and held against radial expansion

by screw means securing the split rings to the end members, said hollow body of insulation extending through the two end members and being open at both ends to permit a natural circulation of cooling air therethrough, and a yielding packing 5 between the end members and the glass tube maintaining the seal between the end members and the glass tube while permitting a limited relative shifting between them under expansion and contraction incident to thermal changes. 10

14. A current limiting resistor for high tension power circuits, comprising a sleeve of insulating material, a pair of metallic members forming electrical terminals and providing radial and axial support for said sleeve with sufficient play 15 relative to said metallic members to permit free thermal contraction and expansion of said sleeve, a resistance wire supported upon a cylindrical surface of the sleeve and being connected electrically to said members, said members having 20 flanges, a glass sleeve extending between said flanges to form an enclosure for said resistance wire, yielding packing between said flanges and said glass sleeve, and insulating means rigidly supporting said members in spaced relation inde- 25 pendently of said glass sleeve and of said sleeve of insulating material.

15. A current limiting resistor for high tension power circuits, comprising a sleeve of insulating material, a pair of metallic members 30 forming electrical terminals and providing radial and axial support for said sleeve said sleeve having sufficient free play relative to said metallic members to permit thermal contraction and expansion, a resistance wire supported upon a cy- 35 lindrical surface of the sleeve and being connected electrically to said members, said members having flanges, a glass sleeve extending between said flanges to form an enclosure for said resistance wire yielding packing between said 40 flange and said glass sleeve, insulating means rigidly supporting said members in spaced relation independently of said glass sleeve and of said sleeve of insulation, and heat radiating flanges thermally in engagement with said mem- 45 bers for dissipating heat therefrom.

16. In a device of the class described, the combination of a sleeve of heat resistant insulation, a pair of rings loosely embracing the sleeve adjacent its ends to permit thermal ex- 50 pansion and contraction of the sleeve relative to said rings, a second sleeve of insulation held in substantially coaxial position with respect to said first sleeve by said rings, a metallic resistor mounted on said first sleeve and enclosed by 55 said sleeves and rings, said rings serving as terminals for said resistor, and means for rigidly supporting said rings in spaced relation, said first sleeve extending through and projecting beyond at least one of said rings. 60

17. In a high tension current limiting resistor, the combination of a pair of spaced metallic end pieces, a sleeve of heat resisting insulation having a resistance wire wound thereupon, said wire being connected to said end pieces, said sleeve being 65 mounted loosely with respect to said end pieces to permit expansion and contraction due to thermal changes produced by variations of current flow through the wire, and rigid supporting means including insulation comprising a solid block of 70 porcelain providing adequate creepage distance for the high tension current, said means constituting the sole means for holding the end pieces in fixed position.

18. In a high tension current limiting resistor, 75

- the combination of a pair of spaced metallic end pieces, a sleeve of heat resisting insulation having a resistance wire wound thereupon, said wire being connected to said end pieces, said sleeve being mounted loosely with respect to said end pieces to permit expansion and contraction due to thermal changes produced by variations of current flow through the wire, rigid supporting means including insulation providing adequate creepage distance for the high tension current, said means holding the end pieces in fixed position, and a vitreous weather resistant sleeve spaced radially from the resistance wire and yieldingly sealed to said metallic end pieces to provide a non-deteriorating enclosure for said resistance wire.
19. In a high tension current limiting device, the combination of a pair of annular metallic end pieces, a resistance wire connecting said pieces, a tubular electrical insulating member open at its ends for ventilation and being adapted to withstand the heat of the resistance wire and being held loosely by said end pieces to permit its
- 5

independent contraction and expansion due to temperature changes, and means independent of the said member and being disposed wholly at one side of said member forming the sole support for holding the end pieces in fixed and insulated relation to each other.

20. In a high tension current limiting device, the combination of a pair of metallic end pieces, a resistance wire connecting said pieces, an electrical insulating member adapted to withstand the heat of the resistance wire held loosely by said end pieces to permit its independent contraction and expansion, due to temperature changes, means independent of the said member forming the sole support for holding the end pieces in fixed and insulated relation to each other, and a sleeve of vitreous weather resistant material yieldingly sealed to the end pieces and cooperating with the end pieces to form an enclosure for said wire resistor.
